ATTOREYS.

UNITED STATES PATENT OFFICE.

MORRIS F. BELL, OF FULTON, MISSOURI.

ADJUSTABLE ROCKING-CHAIR.

SPECIFICATION forming part of Letters Patent No. 224,130, dated February 3, 1880.

Application filed May 1, 1879.

To all whom it may concern:

Be it known that I, MORRIS F. BELL, of Fulton, in the county of Callaway and State of Missouri, have invented a new and Improved Adjustable Rocking-Chair, of which the following is a specification.

Figure 1 is a side elevation of the chair. Fig. 2 is a front elevation of the same.

Similar letters of reference indicate corresponding parts.

The invention consists of the hind legs, A A, of the chair, with lower ends mortised into the rockers B B, curved upward and forward so as to form the side supports for the seat, and these front ends of A A are supported by the front legs, C C. The side pieces, D D, of the chair-back are pivoted at a' to the downward-projecting lugs b' of the legs A A, and are held in position by the arms E E, whose rear ends are pivoted to them.

The head-piece F connects the pieces D D at their tops. The rod G passes through the slots d' and under the chair-seat and through the front ends of the arms E E. This rod has a screw-thread cut on one end, and on this, outside of one of the arms, is the thumb-screw or hand-wheel H, which, being turned, will enable the operator to adjust the back of the chair at the desired angle within the limits of the horizontal movement of the rod in the slots, and to secure it there.

On the rod, between the arms and the bot-

tom side supports, are loose sleeves f' f'', that receive the strain caused by tightening the hand-wheel and prevent the springing inward of the arms.

The seat and back of the chair are continuous, and composed of thin transverse strips I I, of wood or other suitable material, riveted on two or more longitudinal flexible bands, k k, of metal or other suitable material. One end of these bands is secured to the head-piece F, while the other is fastened to the front piece, L, of the seat. Thus both back and seat are formed, that are flexible and will conform themselves to the shape of the occupant. They may be covered with any suitable material or be left exposed, as shown.

Having thus described my invention, I claim as new and desire to secure by Letters Patent.

The combination, in a rocking-chair, with the rockers, seat, and front legs, of the hind legs, A, curved forward and resting on the front ones, the back pieces, D, connected by piece F, and pivoted at a' to lugs b' of said legs, the arms E, pivoted at their rear ends to back pieces, D, and the rod G, passing through as well as adjustable in slots d', as shown and described.

MORRIS F. BELL.
